UNITED STATES PATENT OFFICE.

GEORGE P. ROGERS, OF ATLANTIC CITY, NEW JERSEY.

CLOTHES-WASHER.

1,102,958.

Specification of Letters Patent. Patented July 7, 1914.

Application filed October 18, 1913. Serial No. 795,961.

To all whom it may concern:

Be it known that I, GEORGE P. ROGERS, a citizen of the United States, residing at Atlantic City, in the county of Atlantic and 5 State of New Jersey, have invented new and useful Improvements in Clothes-Washers, of which the following is a specification.

This invention relates to a combined clothes pounder and steamer and has for 10 its primary object the provision of a device of this character which will include a pounding head having a diaphragm intermediate of its ends and provided throughout with a plurality of perforations which are arranged to cause a thorough and broad distribution of the water through the clothes 15 on the upstroke of the device when the latter is used as a pounder.

Another object of the invention is the 20 provision of a device of this character which will be provided with a valved closure which may be adjusted so as to close the chamber of the head to the atmosphere when the device is used as a pounder and which will 25 be operable to regulate the compression of the air in the chamber as the occasion may demand.

A further object of the invention is the 30 provision of a steaming attachment which may be readily applied to or removed from the closure of the pounding head and which may be associated with the head so that direct communication may be established therewith so that the water rising into the 35 head may be conducted into the attachment and discharged therefrom in spray form.

Another object of the invention is the provision of a device of this character wherein 40 the closure thereof may remain intact upon the head of the pounder when it is desired to convert the pounder into a steamer.

A still further object of the invention is the provision of a pounder wherein the chamber thereof will contain a foraminous 45 diaphragm which will be spaced from the closure of the head so as to form therein an intervening compartment in which soap may be placed, if desired, so that the water may become properly impregnated with the soap 50 during the steaming or pounding operation.

Further objects of the invention will appear as the following description is read in connection with the accompanying drawing, which forms a part of this application, 55 and in which—

Figure 1 is a vertical section through the

device. Fig. 2 is a horizontal section taken on the line 2—2 of Fig. 1. Fig. 3 is a section through a portion of the device showing the steaming attachment connected with the closure of the pounding head. Fig. 4 is a side view of the steaming attachment.

The device comprises a pounding head 1 having a substantially semi-spherical upper portion 2 and a cylindrical, vertically disposed lower portion 3, the latter having its lower edges folded, as at 4, so as to reinforce the head at the bottom and to prevent the edges of the head from tearing the clothes when the device is in use. The upper portion 2 is provided with a threaded extension 5 having a relatively large internal diameter for a purpose to be hereinafter described. Intermediate of the ends the head has secured therewithin a circular concavo-convex disk or diaphragm 6 in which perforations 7 are formed at desired points. A closure 8 overlies the upper end of the extension 5 and as shown said closure is provided with a flange 9 having an internal thread 10 which is adapted to receive the thread of the extension. The closure is provided preferably with a flat crown 11.

The crown 11 has formed therein a plurality of passages 12 which are arranged in a circular series. Above the crown is mounted a valve plate 13 having passages 14 therein which are also arranged in a circular series and which are adapted to register or partly register with the passages 12 as the occasion may warrant. The plate 12 is in the form of a flat ring having arcuate slots 15 through which combined guide and retaining stems 16 are extended. These stems may be mounted on the crown 11 of the closure in any well known obvious manner.

Rising from the crown 11 of the closure is a substantially frusto-conical brace 17 through which is extended an interiorly threaded sleeve 18 which has its upper edges rolled over and around the upper edge of the brace, as shown at 19. The lower end of the sleeve 18 is riveted or otherwise secured as at 20 to the central portion of the crown 11.

At the lower end the walls 3 of the head 1 are embraced by a collar 21 having a base 22 which is extended below the edge 4 and provided with an annular series of perforations 23. This construction is preferred in order that jets of water may be expelled in an upward direction and in the direction of

the arrow indicated in Fig. 1 when the pressure in a downward direction is applied to the head. The sleeve 18 hereinbefore referred to receives a threaded metallic portion 24 on a detachable operating handle 25.

In using the device as a clothes pounder the valve plate 13 is adjusted over the passages 12 so as to regulate the emission of air from the head on the down stroke. If desired, and particularly when using the device upon heavy clothes the valve plate 13 is adjusted so as to entirely close the passages 12, thus resulting in the maximum compression of air in the upper portion of the head 1 on the down stroke and consequently increasing the efficiency of the device in properly scattering the water from the head on the up strokes.

When it is desired to use the device for the purpose of steaming clothes in a boiler, I provide a steaming attachment 26. This attachment consists of a vertical pipe 27 which terminates at its lower end in a substantially frusto-conical base 28 overlying the closure 8 and provided with an interiorly threaded flange 29 receiving the threads 30 of the closure 8. The pipe 27, at its connection with the base 28, is embraced by a weight 31 which is adapted to lend stability to the structure and permit the same to properly rest upon the bottom of the clothes receptacle. At the upper end the pipe 27 has removably fitted thereto a sleeve 32 which is provided with a substantially conical shaped spraying head 33 having a series of downwardly and outwardly extending discharge channels 34.

It is obviously understood that when it is desired to use the device as a steamer the handle 25 is removed; that the valve plate 13 is adjusted so that the openings 14 therein register with the openings 12 in the crown

of the closure 8, and that the flange of the base 28 is then threaded onto the extension 5 of the head 1 to thereby establish direct communication between the head and the pipe 27. The device may then be extended into the boiler or clothes receptacle so that the extreme lower edge of the flange 22 will rest on the bottom of the boiler. The water as it becomes heated circulates through the passages 22 and passes in an upward direction in the head 1 and through the perforations 12 and 14 and into the pipe 27 and it is then finally delivered to the spraying head 33 in order that it may be thrown downwardly onto the clothes.

From the foregoing description, taken in connection with the accompanying drawing, the construction and operation of the invention will be readily understood without requiring a more extended explanation.

Various changes in the form, proportion and the minor details of construction may be resorted to without departing from the principle or sacrificing any of the advantages of this invention as claimed.

I claim:—

A clothes washer comprising a head open at its lower end and provided with an outwardly flared foraminous flange, a closure removably fitting the upper end of the head, said closure being provided with a plurality of perforations, and a valve mounted for rotation on the head and having perforations 75 aligning with the perforations of the head on one adjustment of the valve.

In testimony whereof I affix my signature in presence of two witnesses.

GEORGE P. ROGERS.
